UNITED STATES PATENT OFFICE

2,452,438

MOUNTING FOR INVERTED INCANDESCENT MANTLES

Cortland W. Davis, Summitville, Ind., assignor to
The Mantle Lamp Company of America, Chicago, Ill., a corporation of Illinois

Application December 17, 1945, Serial No. 635,561

5 Claims. (Cl. 67—101)

1

The invention includes an improved construction of mantle mounting for supporting inverted incandescent mantles for use in lamps and lanterns of any kind employing a gaseous mixture as fuel, whether produced from liquid hydrocarbon or otherwise. The invention also includes a burner head to be supported on the lower end of the mixing tube of the lamp or lantern, which burner head has in its lower portion a bore for receiving the upper portion of the mantle mounting, which mantle mounting at its upper portion has the general conformation of the bore in the burner head, but is preferably spaced radially a small amount from said bore, so that the upper portion of the mantle mounting is not in contact with said bore. The burner head is provided preferably at the lower end of its said bore, with an annular seat substantially perpendicular to the axis of the burner head, which seat is of small extent radially for engagement with a corresponding seating surface on the mantle mounting, when the mantle mounting is held in its fully raised position relatively to the burner head. The annular seat carried by the burner head and the corresponding seating surface carried by the mantle mounting, provide a tight seal against the flow of fuel mixture between the burner head and the mantle mounting when the device is in use in a lamp or lantern, which prevents the undesirable flow of fuel mixture to the outside of the mantle with the loss in efficiency attending any such leakage, and also prevents the undesirable effect of burning the fuel mixture outside of the mantle.

The spacing of the upper portion of the mantle mounting from the bore in the burner head prevents adhesion between these parts resulting from the corrosive effects of the high temperature to which the parts are subjected in use, and also resulting from minute deposits of solid particles that may result from burning the fuel. The annular seat carried by the burner head, is preferably in the form of an annular lip of small cross-section extending downwardly from the adjacent portion of the burner head, which limits the engagement between the annular seat and the seating surface of the mantle mounting, to line engagement, or substantially so.

The invention also provides a structure for centering the mantle mounting in the bore in the burner head, which preferably comprises a short tubular extension from the burner head below its said annular seat, the inner diameter of said tubular extension being a loose fit on a corresponding portion of the mantle mounting, so that the radial relation between said tubular extension and the mantle mounting will maintain the spaced relation above referred to between the upper portion of the mantle mounting and the bore in the burner head. Below the burner head, the mantle

2

mounting is preferably provided with a grooved conformation to support an inverted mantle by a tie-cord or wire or any other suitable means, and at its lower end the mantle mounting is preferably provided with a screen extending across it to reduce to a minimum any tendency of the fuel mixture to back-fire through the burner head.

In addition to the structure described, the invention provides suitable holding devices between the burner head and the mantle mounting, by which the mantle mounting is firmly held in place with its seating surface in engagement with the annular seat on the burner head, so that leakage of fuel mixture between the burner head and the mantle mounting is avoided, and that at the same time the mantle carried by the mantle mounting is positively supported in proper position for use. The holding devices employed may have any desired form, and as illustrated in the drawings, said devices comprise pins carried by the burner head and projecting inwardly from its said bore to engage cooperating slots in the upper portion of the mantle mounting.

In the preferred embodiment of the invention, the upper portion of the mantle mounting is frusto-conical and diverging downwardly, and the bore in the burner head is similarly formed, so that although the upper portion of the mantle mounting is located near the bore in the burner head, it is at the same time substantially spaced from said bore to avoid adhesion between said parts. In the preferred embodiment of the invention illustrated in the drawings, the slots in the upper portion of the mantle mounting are preferably of the "bayonet joint" variety, each of said slots including an axially extending portion for receiving the inner end of the corresponding pin carried by the burner head, in registering the slots in the mantle mounting with the pins in the burner head, each of said slots further including a circumferential portion at a small angle to a horizontal plane, so that a small angular movement of the mantle mounting after registry of its slots with the said pins, will raise the mantle mounting and press its seating surface into firm engagement with the annular seat carried by the burner head, and securely hold the mantle mounting in that position. It is preferable that the mantle mounting shall be made of thin sheet metal or alloy to conserve material and to reduce heat conduction to the burner head to a minimum. The frusto-conical form of the upper portion of the mantle mounting permits the axial portions of the slots to be closed at their upper ends, since the radial distance between the upper ends of the said axial portions is substantially less than the radial distance between the ends of the corresponding pins in the burner head, which permits the pins to enter the axial portions of the mantle mounting slots, in registering the mantle mount-

ing with the burner head in proper position to effect the holding of the mantle mounting in place by means of said pins. Other constructions of devices for holding the mantle mounting in the burner head may be used, if preferred, as below described.

The present invention is the result of many years of practical manufacturing experience in making mantle mountings and burner heads, and it includes a mantle mounting, which provides a tubular structure of thin sheet metal having a grooved lower portion facilitating the factory application in a proper manner of an incandescent inverted mantle, and having an upper portion constructed as above described.

The conical form of the mantle mounting also has the advantage of gradually and uniformly expanding the fuel mixture as it passes through the upper portion of the mantle mounting, without turbulence and undesirable eddying currents, at the same time correspondingly decreasing the velocity of flow of the mixture, so that the fuel mixture is delivered from the mantle mounting and to the flame in the mantle below the mantle mounting, in a uniformly distributed condition throughout the stream of discharged fuel mixture and at the uniform velocity throughout said stream that is required to produce the size and shape of the flame needed to effectively and uniformly incandesce all parts of the mantle.

The present invention is an improvement on the invention disclosed in Patent No. 2,023,467 granted December 10, 1935. The present invention retains all of the advantages of said prior invention, and at the same time avoids its disadvantages, first, by moving the joint-sealing surface of the mantle mounting to the lower end of the bore in the burner head, where said joint-sealing surface is preferably substantially perpendicular to the axis of the mantle mounting to cooperate with a corresponding surface of the burner head, the centering of the mantle mounting in the bore being effected by a short tubular extension from the burner head around the portion of the mantle mounting of largest diameter, without requiring the mantle mounting to be larger axially than would be required if the centering function were absent; and second, by making the portion of the mantle mounting within the bore in the burner head solely for supporting purposes for the mantle mounting, and by so spacing the said upper portion of the mantle mounting from the bore in the burner head that serious adhesion between the parts due to heating and corrosion, cannot occur. In addition, the present invention provides the further advantages, due to the conical form of the upper portion of the mantle mounting, that a simple form of pin and slot supporting connection may be employed without the extension of the slots through the upper end of the mantle mounting and thereby weakening it, and that the expansion of the fuel mixture is uniformly effected, thereby most efficiently producing uniformly distributed incandescence of the mantle.

The invention is generically regarded as including a mounting preferably of sheet metal, for location in the interior of a burner head to support an inverted incandescent mantle, which mantle mounting is provided at its lower end portion with means for the attachment of such a mantle, and is also provided above said attachment means with an annular seating portion for engagement with the burner head by raising the mantle mounting to press said seating portion

tightly against the burner head and thus produce a seal between the mantle mounting and the burner head, including the structure of the parts and their relationship specifically described below and all equivalent modifications thereof producing substantially the same result, said mantle mounting also being provided with means for so raising said mantle mounting relatively to the burner head, which raising means includes the structure specifically described below and equivalents thereof. For it is thought that the gist of the invention resides in so constructing the mantle mounting and the burner head, that, with the mantle mounting located in the interior of the burner head, raising the mantle mounting relatively to the burner head presses a portion of the mantle mounting tightly against a seating surface of the burner head to produce a seal between the mantle mounting and the burner head, regardless of the specific structure and location of parts involved in so doing.

It is the object of the invention to produce a mantle mounting having the construction, operation and advantages described, also the combination of such a mantle mounting and assembled mantle, and also the combination of such a mantle mounting with a burner head constructed as described to cooperate therewith; for the disclosed invention is regarded as including said improved mantle mounting, said mounting and mantle assembly, and also said combination of mantle mounting and burner head.

My invention will be best understood by reference to the accompanying drawings illustrating a preferred embodiment thereof, as well as modified forms of said holding devices, in which—

Fig. 1 shows in front elevation a burner head and mantle mounting in accordance with my invention and in assembled relation,

Fig. 2 shows in side elevation to an enlarged scale and partially in vertical, sectional view, the preferred mantle mounting illustrated in Fig. 1,

Fig. 3 is a plan view of the structure shown in Fig. 2,

Fig. 4 is a vertical, sectional view of an enlarged scale through the assembled burner head and mantle mounting, taken along the line 4—4 in Fig. 1, and shows the preferred form of the invention.

Fig. 5 is a vertical, sectional view through the burner head illustrated in Fig. 4, taken along the line 5—5 in Fig. 4,

Fig. 6 shows in a view similar to Fig. 4 a modified form of devices for holding the mantle mounting in place in the burner head,

Fig. 7 shows in a view similar to Fig. 4 a further modified form of devices for holding the mantle mounting in the burner head, and

Fig. 8 shows in plan view the mantle mounting illustrated in Fig. 7, this view of the mantle mounting being taken along the line 8—8 in Fig. 7.

Similar numerals refer to similar parts throughout the several views.

As shown in Fig. 1, the invention includes a burner head 1 supported on the lower end of a mixing tube 2, the burner head having mounted in its lower portion, a mantle mounting 3 provided with a circumferential groove 4 for receiving a binding cord or wire used to secure the upper end of an inverted incandescent mantle 5, to said mantle mounting. The mantle 5 may be of any kind susceptible of use as an inverted incandescent mantle and is shown merely for illustrative purposes.

As shown in Figs. 2 and 3, the mantle mounting 3 is of formed sheet metal and is provided with a frusto-conical upper portion 6 diverging downwardly, which portion 6 terminates at its lower end in a seating portion 7, the upper surface of which comprises an annular seating surface substantially perpendicular to the axis of the mounting 3. Below the seating portion 7, the mantle mounting is provided with a short cylindrical portion 8, below which the mantle retaining groove 4 is formed in the mounting. Below the groove 4, the lower end portion of the mounting 3 is formed to engage and support a wire screen 9 across the discharge end of the mantle mounting, by pressing the end of the mounting inwardly and upwardly against the screen to hold the latter against the inner surface of a wall of the groove 4.

As shown in Fig. 4, the burner head 1 is provided in its lower portion with a frusto-conical bore 10 diverging downwardly and terminating in an annular lip 11 substantially perpendicular to the axis of the burner head 1, said lip constituting an annular seat for engagement with the seating portion 7 of the mantle mounting 3. Below the lip 11, the burner head 1 is provided with a short tubular extension 12, having an inner diameter which fits easily around the portion 8 of the mantle mounting. The frusto-conical upper portion 6 of the mantle mounting is of substantially the same angle as the frusto-conical bore 10 and also diverges downwardly, and as shown, the seating portion 7 of said mantle mounting is in sealing engagement with the annular lip 11. The parts described are so proportioned that the relation between the cylindrical portion 8 and the tubular extension 12, maintains a substantial spacing 13 between the bore 10 and the portion 6 of the mantle mounting, so that the use of the structure will not result in adhesion between the bore 10 and the mantle mounting portion 6, the conical form of the portion 6 at the same time providing for the progressive expansion laterally of the fuel mixture as it moves through the mantle mounting so that said mixture is uniformly distributed when it reaches the screen 9 and with a minimum of retardation to its flow.

As more clearly shown in Fig. 5, the burner head 1 is provided with pins 14 substantially perpendicular to the bore 10 and extending inwardly towards each other a short distance inside of said bore. As shown, two of said pins 14 are employed which are diametrically opposite each other in said bore, although a larger number of pins may be so used if preferred. The frusto-conical portion 6 of the mantle mounting is provided with slots 15 for receiving the inner ends of the pins 14, each of said slots including an axial portion 16 continuing at its lower end into a circumferential portion 17, the latter portion being inclined a small amount to a plane perpendicular to the axis of the mantle mounting, so that the portions 16 of said slots may serve as a means for registering the slots with the inner ends of the pins 14, and that the portions 17 of said slots may serve by a small angular movement of the mantle mounting, to raise the mantle mounting upwardly and hold it with its seating portion 7 firmly pressed against the annular lip or seat 11. It will be noted that the axial portions 16 of the slots 15 are closed at their upper ends, thereby imparting stiffness to the upper portion of the mantle mounting. The tapered formation of the upper portion of the mantle mounting permits

the entry of the inner ends of the pins 14 into the axial portions 16 of the slots 15, quite as effectively as though the said axial portions 16 of said slots opened through the upper end of the mantle mounting.

As shown in Figs. 2, 3 and 4, the frusto-conical portion 6 of the mantle mounting 3, is preferably provided with opposite tongues 6a, made by slitting the upper edge portion of the mantle mounting, which tongues are bent outwardly at their upper ends to have end engagement with the bore in the burner head, so that when the mantle mounting is pressed upwardly in said bore to engage the pins 14 in the portions 17 of the slots 15, the upper ends of the tongues 6a press outwardly with substantial pressure and frictional engagement against the surface of said bore, to prevent turning movement of the mantle mounting in said bore unless the mantle mounting is positively turned relatively to the burner head. In this manner, accidental separation of the mantle mounting from the burner head is avoided as long as the pins 14 are in the portions 17 of the slots 15. This action of the tongues 6a also tends to center the mantle mounting in the bore in the burner head.

A modified construction of the invention is illustrated in Fig. 6, in which the burner head 18 is provided with a bore 19 which is cylindrical, the upper portion 20 of the mantle mounting 21 being cylindrical and tubular and substantially spaced as indicated at 22 from the bore 19 to avoid adhesion between the mantle mounting and said bore. The burner head 18 is provided at the lower portion of its bore 19, with an annular seat substantially perpendicular to the axis of the burner head 18, in the form of an annular lip 23 for engaging the upper seating surface of an annular seating portion 24 of the mantle mounting, extending outwardly from the lower end of the tubular portion 20, substantially perpendicular to the axis of the mantle mounting. The burner head 18 is provided below the annular lip 23 with a short tubular extension 25 which is a loose fit around a corresponding portion 26 of the mantle mounting, the mantle mounting 21 being provided with a mantle supporting groove 27 and screen 28 as and for the purposes above described. With the construction of Fig. 6, the mantle mounting is held in the burner head by pins 29 carried by the head 18 and extending into the bore 19, engaging bayonet slots 30 in the portion 20 of the mantle mounting. In this case, however, because of the cylindrical form of the portion 20, the slots 30 open through the upper end of the mantle mounting. The construction illustrated in Fig. 6 operates in the same manner as the construction illustrated in Fig. 4, in avoiding adhesion between the upper portion of the mantle mounting and the bore in the burner head, and it also effectively seals the annular lip 23 against a corresponding seating surface of the mantle mounting in substantially the manner and for the purposes described in connection with Fig. 4.

In the modified construction shown in Figs. 7 and 8, the burner head 1 and pins 14 are the same as shown and described in connection with Figs. 4 and 5, the difference being in the construction of the mantle mounting. The mantle mounting 31 shown in Figs. 7 and 8 is of the same general form as the mantle mounting 3 and has the same relation to the burner head 1 as described in connection with Fig. 4, the difference being the structure employed to cooperate with the inner

ends of the pins 14. The upper portion 32 of the mantle mounting is frusto-conical and diverging downwardly and substantially spaced from the bore 10 as above described, and said mantle mounting is provided with an annular seating portion 33 and tubular portion 34 having the same relation to the annular lip 11 and to the tubular extension 12 as above described for the structure shown in Fig. 4. The mantle mounting 31 is provided in its upper conical portion 32, with axial grooves 35 beginning at the upper end of the mantle mounting, for engaging the inner ends of the pins 14, said grooves at their lower ends continuing through the wall of the mantle mounting in the form of slots for receiving the inner ends of the pins 14. The material of the mantle mounting 31 is formed at said slots, into inwardly extending spring tongues 36, pressing against the upper edges of the inner ends of the pins 14, when the mantle mounting is seated against the annular lip 11, which spring tongues press the mantle mounting upwardly in the burner head and thus hold the mantle mounting in place and support the mantle attached to the mantle mounting in position for use. When it is necessary to remove the mantle mounting 31, all that is required is to exert a downward axial thrust on the mantle mounting to move the spring tongues 36 over the inner ends of the pins 14 and the mantle mounting is thereby released from the burner head 1.

The constructions described provide for the ready and proper connection of the mantle mounting with the burner head with a minimum of effort and thought on the part of the user, and they also provide for as readily removing a used mantle mounting without adhesion and binding with the burner head for replacement purposes, thus greatly facilitating the practice where desired, of incorporating the mantle mounting in the mantle assembly, and thereby insuring the use of a new and uncorroded mantle mounting and screen with each new mantle.

While I have shown my invention in the particular embodiment above described, I do not limit myself thereto as I may employ equivalents thereof without departing from the scope of the appended claims.

Having thus described my invention, what I claim is:

1. Means for supporting an inverted incandescent mantle on a burner head having an upwardly converging conical bore in its lower portion and an annular seat extending outwardly from the lower end of said bore and having locking pins extending into said bore, which mantle supporting means is characterized by and comprises a mantle mounting of sheet metal having an upper portion of a shape corresponding to said bore and also having at the lower end of its upper portion an outwardly extending annular portion for engaging said seat, the upper portion of said mantle mounting having locking slots for engaging said pins to hold said mantle mounting in tight engagement with said seat.

2. Means for supporting an inverted incandescent mantle on a burner head having an upwardly converging conical bore in its lower portion and an annular seat extending outwardly from the lower end of said bore and having locking pins extending into said bore, which mantle supporting means is characterized by and comprises a mantle mounting of sheet metal having an upper portion of a shape corresponding to said

bore and also having at the lower end of its upper portion an outwardly extending annular portion for engaging said seat, the upper portion of said mantle mounting having locking slots for engaging said pins to hold said mantle mounting in tight engagement with said seat, the upper portion of said mantle mounting being somewhat smaller laterally than said bore to leave a small clearance space between said upper portion and said bore.

3. Means for supporting an inverted incandescent mantle on a burner head having an upwardly converging conical bore in its lower portion and an annular seat extending outwardly from the lower end of said bore and having locking pins extending into said bore, said burner head also having a tubular extension projecting downwardly from the outer edge of said seat, which mantle supporting means is characterized by and comprises a mantle mounting of sheet metal having an upper portion of a shape corresponding to said bore and also having at the lower end of its upper portion an outwardly extending annular portion for engaging said seat, the upper portion of said mantle mounting having locking slots for engaging said pins to hold said mantle mounting in tight engagement with said seat, the upper portion of said mantle mounting being somewhat smaller laterally than said bore to leave a small clearance space between said upper portion and said bore, said mantle mounting below and from the outer edge of its said annular portion, having a cylindrical portion of an external diameter to fit said tubular extension to center said mantle mounting in said bore.

4. A sheet metal mounting for location in the interior of a burner head to support an inverted incandescent mantle, said mounting including at its lower end portion means for the attachment of an incandescent mantle, and above said attachment means having an annular seating portion for engagement with a burner head, said mounting also having a frusto-conical upper portion above said seating portion and converging upwardly from said seating portion and provided with means for raising said seating portion tightly against the burner head.

5. A sheet metal mounting for location in the interior of a burner head to support an inverted incandescent mantle, said mounting including at its lower end portion means for the attachment of an incandescent mantle, and above said attachment means having an annular seating portion for engagement with a burner head, said mounting also having an upper end portion provided with means for raising said seating portion tightly against the burner head, the upper end portion of said mounting having spring tongues projecting outwardly a substantial amount from the lateral surface of said upper end portion for frictional engagement with an inner surface of said burner head.
